UNITED STATES PATENT OFFICE.

ARTHUR F. REMTER, OF ARTOIS, CALIFORNIA.

SIGNALING DEVICE FOR AUTOMOBILES.

Application filed May 20, 1927. Serial No. 192,982.

This invention relates to signaling devices and pertains particularly to a signal designed primarily for use upon closed motor vehicles.

5 The primary object of the present invention is to provide, in a manner as herein-after set forth, a direction indicator of such construction as to permit its use upon closed vehicles, giving a clear and unmistakable 10 signal without the necessity of the operator of the machine extending his hand beyond the confines thereof.

The invention broadly contemplates the provision of a single member formed to 15 provide a pair of relatively long end arms arranged on parallel lines and extending in opposite directions and an intermediate portion extending at right angles to and connecting the inner ends of the end arms. The 20 said intermediate portion is designed to be extended through a front corner post of the machine body, lying longitudinally of the machine so that one of the arms will be, when in horizontal position, extended beyond the side of the body while the other 25 end arm will be extended in a horizontal position transversely of the interior of the machine. Suitable means is associated with the inner arm for maintaining the device in 30 any set position.

Another object of the present invention is to provide in a manner as hereinafter set forth, a direction indicating signal of the character above described, which shall be of 35 simple but strong and durable and efficient construction, easy to operate, install and comparatively inexpensive to manufacture.

Numerous other objects and advantages of the present invention will become apparent 40 as the description of the same proceeds, and the invention will be best understood from a consideration of the following detailed description taken in connection with the accompanying drawing forming a part of this 45 specification, with the understanding, however, that the invention is not confined to any strict conformity with the showing of the drawing but may be changed or modified so long as such changes or modifications mark no material departure from the 50 salient features of the invention as claimed.

In the drawing:

Figure 1 shows conventionally the upper portion of a motor vehicle in front elevation, 55 showing the device embodying this invention applied thereto.

Figure 2 is a view looking from the interior of the machine showing the construction of the device as seen from the interior 60 of the car.

Figure 3 is a plan view of the indicator structure exclusive of the outer end portion of the outer arm, and

Figure 4 is a section taken substantially 65 upon the line 4—4 of Figure 3.

Referring now to the drawing in detail 70 wherein like numerals of reference indicate corresponding parts throughout the several views, the numeral 1 indicates conventionally the front and upper portion of a closed automobile of the sedan type having the front upright posts 2 and wind-shield 3 mounted therebetween. As is shown, in Figure 3, the post 2 has a front inwardly extending portion 4 against which the edge 75 of the wind-shield abuts.

The device embodying the invention comprises a casing 5, which is positioned against the inner side of the transversely extending portion 4 of the body post 2 at the side occupied by the driver of the vehicle and this box or receptacle is closed by a plate 6 which is of greater width than the box and has the projecting edge portion 7 curving outwardly and downwardly at its upper end as indicated at 8 and provided intermediate its ends with a plurality of notches 9, in the present instance, three notches being employed. The front and rear sides 10 and 11 respectively of the casing 5 are provided with 85 apertures 12, in alignment transversely of the casing.

The single moving part of the present direction and signal indicator comprises an elongated rod indicated generally by the numeral 13. This rod is formed to provide an outer arm 14, a slightly curved inner arm 15 which terminates in a handle ball or knob 16, and an intermediate connecting portion 17 which connects the inner ends of the arms 14 and 15 as will be readily seen upon reference to Figure 3. As shown in this figure, the intermediate portion 17 is arranged substantially at right angles to the arms 14 and 15 and extends through the aligned apertures 12 of the walls 10 and 11, of the casing and through the laterally and inwardly directed portion 4 of the post against which the casing 5 is secured. The arm 15 comprises the actuating member and handle of the signal device and the arm 14 comprises the signal arm proper, carrying at its outer end a sig- 90 95 100 105 110

nal member of any desired form, the type here shown being in the form of an arrow head indicated at 18. This head 18 may be appropriately colored so that it will readily 5 attract notice when swung outwardly from the body in the manner indicated in dotted lines in Figure 1.

As will be readily understood from the 10 showing of Figure 3, the arm 15 rides over the edge 7 of the casing plate 6 when rotated upon the intermediate portion 17 which acts as a shaft and when so rotated, the arm will engage in one or another of the notches 9.

In order to maintain the arm 15 in any 15 one of the notches 9, there is placed about the arm, within the casing 5; a coil spring 19, one end of which bears against the wall 10 of the casing while the other end bears against a pin 20 which is fitted through the 20 intermediate portion 17 of the signal device. From this it will be readily understood that when the actuating arm 15 is swung upwardly to bring the signal member or head 18 to position in front of the vehicle post 2 25 as indicated in dotted lines in Figure 1, the spring will act to draw the arm 15 inwardly against the adjacent wall of the box. When it is desired to give a signal, the knob 15 of the arm 16 is grasped and the arm swung 30 downwardly causing it to ride over the curved and notched edge 8 of the flange 7, thus moving the intermediate portion longitudinally and compressing the spring 20, and further movement downwardly of the 35 arm 15 will cause it to engage one of the notches 9 whereupon it can be released and will be held in the desired signaling position.

Having thus described my invention what 40 I claim is:

1. In a signal device of the class described, a casing having one of its walls provided with a portion projecting beyond an adjacent wall and formed with a series of notches, a member comprising a portion mounted for rotation in the second mentioned wall of the casing and the wall oppo-

site thereto, and an operating arm and a signal arm extending in opposite directions from the opposite ends of the said portion of the member, the operating arm being angularly adjustable to effect adjustment of the signal arm and being engageable selectively in the notches in the projecting wall portion to be held in its positions of adjustment. 55

2. In a signal device of the class described, a casing having one of its walls provided with a portion projecting beyond an adjacent wall and formed with a series of notches, a member comprising a portion 60 mounted for rotation in the second mentioned wall of the casing and the wall opposite thereto and adapted to have longitudinal shifting movement, an operating arm and a signal arm extending in opposite directions from the opposite ends of the said portion of the member, the operating arm being angularly adjustable to effect adjustment of the signal arm to different positions 65 of angular adjustment and likewise adjustable to position engaging the inner side of the projecting portion of the first mentioned wall of the casing to position the signal arm out of display position, the said operating arm being engageable selectively in the 70 notches in the said projecting wall portion whereby to be held in its different positions of angular adjustment, an abutment upon the said intermediate portion of the said member within the casing, and a spring 75 upon the said intermediate portion engaging at one end against the abutment and at its other end against the second mentioned wall of the casing and constituting means for yieldably urging the intermediate portion, in its shifting movement, in a direction to hold the operating arm in engagement with the projecting wall portion of the casing and likewise in position engaged behind said wall portion, in the non-display position of the signal arm. 85

In testimony whereof I affix my signature.

ARTHUR F. REMTER.
